(57) **CLAIM**

The ornamental design for an auxiliary bicycle fender noise generator, as shown and described.

DESCRIPTION

FIG. 1 is a perspective view of an auxiliary bicycle fender noise generator showing my new design with a portion of a bicycle shown in dashed lines which bicycle is not part of my design;

FIG. 2 is a right side view thereof;

FIG. 3 is a left side view thereof;

FIG. 4 is a top plan view thereof;

FIG. 5 is a bottom plan view thereof;

FIG. 6 is a front elevational view thereof; and,

FIG. 7 is a rear elevational view thereof.
